BY *Victor J. Evans*

ATTORNEY

WITNESS:

UNITED STATES PATENT OFFICE.

SYLVESTER H. BAILEY, OF SUPERIOR, WISCONSIN.

CONTAINER.

Application filed March 13, 1923. Serial No. 324,860.

To all whom it may concern:

Be it known that I, SYLVESTER H. BAILEY, a citizen of the United States, residing at Superior, in the county of Douglas and State of Wisconsin, have invented new and useful Improvements in Containers, of which the following is a specification.

The object of the present invention is to produce a cigarette case of a construction to snugly receive therein a package of cigarettes and provided with means whereby the outer face and the upper end of the container for the cigarettes will be slitted, said holder comprising two substantially rectangular members that are hinged at one of their confronting edges and provided with a means for slitting the paper container on one of its opposite edges, while means on the last mentioned edges are provided for holding the case in closed condition, the construction being such that cigarettes may be individually withdrawn from the package or container thereof.

To the attainment of the foregoing and other objects which will present themselves as the nature of the invention is better understood, reference is to be had to the drawing which accompanies, and which forms part of this application.

In the drawing:—

Figure 1 is a perspective view of a cigarette holder in accordance with this invention.

Figure 2 is a similar view showing the holder in open position.

Figure 3 is an approximately central transversal sectional view through the device showing the same in closed position.

As disclosed by the drawing, my cigarette container comprises two substantially box-like members 1 and 2 respectively. The members 1 and 2 are hingedly connected at

one of their confronting edges, as indicated by the numeral 3, while latching means 4 is provided upon the outer edges thereof. On the outer edge of the section 2 there is slidably arranged a knife 5, the sharpened edge of which being inwardly directed. This knife is movable both over the edge and one of the ends of the section, whereby the paper container 6 for cigarettes may be centrally severed to disclose the cigarettes therein. By opening the container, the cigarettes may be individually withdrawn therefrom.

The container may be highly ornamented and is of such construction as to be conveniently carried in the pocket of the user. In addition to this, the cigarettes are retained in a moist condition when the container is closed and also, if desired, cutting means other than the knife 5 may be provided for slitting the paper container for the cigarettes, such for instance as guiding a knife between the confronting edges of the sections 1 and 2.

The knife can be stationary on one end of the section 2 if desired, and the knife may be provided with a guard to prevent cutting into the cigarettes.

Having described the invention, I claim:—

A cigarette case designed to receive therein a package of cigarettes, comprising two substantially rectangular box-like sections hingedly connected at one of their confronting edges, latching means for the sections on the opposite edges thereof, a knife operatively mounted on the outer edge of one of the sections, and said knife designed to be slid along the edge of the said section to slit the package containing the cigarettes whereby cigarettes can be individually drawn therefrom when the case is opened.

In testimony whereof I affix my signature.

SYLVESTER H. BAILEY.
